UNITED STATES PATENT OFFICE.

JAMES A. GRAY, OF SAN FRANCISCO, CALIFORNIA, ASSIGNOR TO AMERICAN CAN COMPANY, OF SAN FRANCISCO, CALIFORNIA, A CORPORATION OF NEW JERSEY.

MULTIPLE-DISK-CUTTING APPARATUS.

1,351,951.

Specification of Letters Patent.

Patented Sept. 7, 1920.

Application filed January 6, 1919. Serial No. 269,783.

To all whom it may concern:

Be it known that I, JAMES A. GRAY, a citizen of the United States, residing at the city and county of San Francisco and State of California, have invented certain new and useful Improvements in Multiple-Disk-Cutting Apparatus, of which the following is a specification.

The hereinafter described invention relates to an apparatus for the multiple cutting of gasket disks from flat liner material for the formation therefrom of gasket ring liners for use in connection with lining of can ends employed in the hermetic sealing of cans or metallic vessels containing food products, the object of the invention being the production of an efficient, economic and rapidly operating apparatus for simultaneously cutting from a traveling web of liner material a plurality of disks, the disposition of the cutting mechanism relative to the traveling web being such that the disks are cut or severed from the web with the least possible waste of liner material and in its preferred embodiment the apparatus employed operates on two continuously traveling superposed webs of liner material, whereby on each reciprocating stroke of the cutting punches of the apparatus there is not only removed or cut a plurality of disks from a traveling web of liner material, but equally so a plurality of disks from a plurality of superposed traveling webs of liner material.

The purpose of the present apparatus is the severing or cutting from a web of liner material disks from which ring liners are subsequently severed by separate or independent mechanism, which cut ring liners are for use in connection with the lining of can ends for seaming to can bodies or metallic containers.

In order to comprehend the invention reference should be had to the accompanying sheet of drawings, wherein an apparatus of preferred form is illustrated and described.

Figure 1 is a view in side elevation of the apparatus illustrating the rolls for the holding of webs of papers and the discharge apron applied thereto, said view illustrating the line of travel of the fibrous superposed webs of liner material and the means for conveying the same past the cutting mechanism and from within the sphere thereof

onto the discharge mechanism, the position 55 of the reciprocating punches for the severing of the disks from the traveling webs of liner material, and the disposition of the cut disks after the severance thereof from the said material.

Fig. 2 is a sectional view in elevation viewed from the discharge end of the machine, the discharge mechanism being removed, said view being taken on line 2—2 Fig. 1 of the drawings, and viewed in the 65 direction of the arrows.

Fig. 3 is a transverse sectional view taken on the line 3—3 Fig. 1 of the drawings and viewed in the direction of the arrows, said view illustrating the position of the reciprocating slides which carry the cutting punches.

Fig. 4 is a similar view taken on the sectional line 4—4, Fig. 1 of the drawings and viewed in the direction of the arrows, said 75 view illustrating the fibrous webs passing through the apparatus and disclosing the staggered relation of the cut-out portions of said web carried beyond or past the cutting mechanism and illustrating the drive mechanism for actuating the feed rolls for advancing the webs of liner material through the apparatus and the means for actuating the discharge apron of the apparatus.

Fig. 5 is a part broken sectional detailed 85 view of the mechanism for feeding the webs of liner material through the apparatus and the position of one of the cutting punches and dies, said view illustrating the buckling of the traveling webs of liner material while 90 momentarily held during the action of cutting mechanism for the removal therefrom of disks of liner material, disclosing the discharge apron for the cut liner material and one of the magazines for receiving the cut 95 disk blanks.

Fig. 6 is a broken sectional detailed view of one of the cutting mechanisms taken on the line 6—6, Fig. 4 of the drawings.

Fig. 7 is a fragmental detailed view of the 100 rear end of one of the holders for the cut disk blanks illustrating the cut disk as supported upon the rods constituting the magazine or holder and held against the friction block thereof.

In the drawings, the numeral 1 is used 105 to indicate a suitable supporting frame capable of sustaining the operating parts

of the apparatus, the said frame being provided with a rear or back wall member 2 in front of which the webs of liner material are adapted to pass or travel as moved 5 through the machine, the said frame and its backing 2 being in the present case vertically disposed. To the frame 1 and in advance of the backing plate 2 is secured in the present case an obliquely disposed support 3 which is detachably held to the frame 1 and spaced from the backing plate 2 by means of the bolts 4, which secure or unite the bracket extension 5 of the said support 3 to the frame structure 1. The obliquely disposed supporting plate or member 3 is provided with a series of guide-ways 6 formed by the angle plates 7 secured to the said outer face of the said support 3 and within which said guide-ways are mounted 10 for reciprocating movement a plurality of slides 8, Figs. 1, 3 and 6 of the drawings. Each reciprocating slide 8 is united to a driven shaft 9 by means of the pivotally connected rod 10 which rods in turn are connected to the crank heads 11 secured at intervals to the said shaft 9. At its inner end each of the reciprocating slides has secured or united thereto in any suitable manner a punch 12, Fig. 6 of the drawings. The crank shaft 9 is driven from a power shaft 13, through the medium of a pinion 15 mounted thereon meshing with the gear 16, secured to the upper extremity of the said crank shaft 9, Figs. 1 and 2 of the drawings, the drive shaft 13 being driven from any suitable outside source of power by means of a power belt, not shown, working over the belt pulley 14 secured to one end of the said drive shaft. On the drive shaft 13 is mounted a worm pinion 16', Fig. 4 of the drawings, which meshes with a worm 17 secured to a transverse shaft 18 mounted in suitable bearings in the frame 1 and situated in a plane above and at substantially 40 right angles to that of the drive shaft 13. At one end the shaft 18 carries a belt pulley 19, over which works a belt 20 adapted to drive a belt pulley 21 secured to a transverse shaft 22 working in bearings at the lower 45 end of the frame 1. The said shaft 18 has secured thereto a roll 23 intermediate of its bearings and at its end opposite to that carrying the belt pulley 19 is secured a pinion 24, which pinion meshes with a similar 50 pinion 25 secured to one end of a transverse shaft 26 arranged in advance of the roll 23 and parallel with the shaft 18. To the shaft 26 is secured a feeding roll 27, Fig. 2 of the drawings.

60 In the present case the apparatus is illustrated as adapted for the carrying or moving of two superposed webs of paper therethrough, the rolls 28 and 29 of liner material being mounted or supported in a suitable holder 30 arranged a distance at the

rear of the frame 1 and connected at the upper end to the said frame structure by means of the longitudinally disposed support 31, within which are mounted a plurality of transversely disposed idler rolls 32. 70 The superposed webs 28' and 29' of the rolls 28 and 29 respectively extend upwardly and move over the idler rolls 32 of the support 31, the free ends thereof extending downwardly between the feed rolls 23 and 27 75 and beneath the delivery roll 33, which maintains a tension thereon and directs or delivers the same onto the longitudinally disposed upwardly inclined endless traveling apron 34, the said superposed webs of 80 liner material during their downward course of travel passing between the alined reciprocating punches 12 and the hollow fixed cutting dies 12', Figs. 1, 5 and 6 of the drawings. There is a cutting die 12' for each 85 reciprocating punch 12, each cutting die being arranged in horizontal alinement with its associated punch 12. These dies 12' are secured within longitudinally disposed spaced openings 35 of the fixed backing 90 plate 2 of the apparatus, and project a distance in advance thereof. As the webs of liner material travel between the punches 12 and the cutting dies 12' the said punches 12 coact with the dies 12' on the inwardly 95 reciprocating stroke of the slides 8 to cut out or sever from the webs of liner material a plurality of core pieces 36, which core pieces are gradually forced through the hollow dies 12' and the circular openings 35 100 of the fixed backing plate 2 and move onto the holder or magazine 37, which holders or magazines in the present case consist of a plurality of spaced outwardly projecting rods or supports 37, Figs. 1, 5, 6 and 7 of 105 the drawings. It will thus be seen that on each inwardly reciprocating stroke of the slides 8, there is cut through the medium of the punches 12 and the dies 12' a plurality 110 of disk blanks or core-pieces 36, which cut disks are delivered onto the magazine or holder 37 until a given number has accumulated thereon, which are then removed for action thereon of independent mechanism for the cutting therefrom a gasket ring liner 115 of a diameter suitable to fit the flange of a can end. The disk blanks as cut from the webs of liner material move onto the support or holder 37 against a movable friction block 37' which maintains the disk blanks 120 in vertical position, it being understood that the said block 37' gives outwardly to the pressure of the core-pieces thereagainst. The superposed webs of liner material are fed into the machine through the action of 125 the feed rolls 23 and 27, and as the movement of the webs is a continuous one it is obvious that as the cutting punches operate thereon for the cutting on a single stroke a plurality of disks therefrom there is a 130

momentarily arresting of the downward travel of the webs below the cutting punches, hence a slight buckling of the webs between the feed rolls and the punches, Fig. 5 of the drawings, which buckling is disposed of by the weight of the traveling webs when freed on the outward or return reciprocating stroke of the cutting punches to release the said webs. It is by reason of this momentary buckling of the webs which is provided for, that permits of the continuous feed of the webs of liner material. The transversely disposed roll 33 acting on the webs at the lower portion of the machine serves to maintain or hold the webs under tension and to guide and direct the free ends of the traveling webs onto the endless traveling conveyer or apron 34, which apron or conveyer travels over the rollers 38 and 38', the roll 38 being driven by the belt 20, which belt is so run as to train over the belt rolls 19, 21, 21^a and 21^b, Figs. 1, 2 and 4 of the drawings.

While the reciprocating slides carrying the punches 12 have been illustrated as extending obliquely to the path of travel of the superposed webs of liner material, it is apparent that such an arrangement is not essential, inasmuch as the said punches may be disposed transversely to the path of travel of said webs of liner material. However, by arranging the support 3 obliquely I am enabled to cut on a single stroke from a web of given width a greater number of disk blanks than could be cut from the same width of web of liner material when the cutting punches are disposed transversely to the line of travel of the said webs, and it is for the purpose of securing the cutting of the greatest possible number of disks on a single action of the cutting punches that the punches are arranged in a line obliquely to that of the path of travel of the webs of liner material. In the present case, the construction of the apparatus is such that the superposed webs of liner material move in a vertical path and the reciprocating punches in a path of movement at substantially right angles thereto, but it is obvious that by throwing the frame structure from a vertical to a horizontal position the line of travel of the webs of liner material would be longitudinal instead of vertical, and in such case the disposition of the series of cutting punches would be relatively vertical in relation to the width of the superposed longitudinally traveling webs of liner material.

The disposition of the reciprocating cutting punches is such relative to the travel of the webs of liner material as to permit of the cutting of the disk blanks in staggered relation, thereby causing the least possible waste of liner material and reducing the cost incident to the production of the disk blanks to a minimum, which is an essential

feature in connection with the supplying of can ends lined with gaskets cut from disks of liner material.

While I have illustrated and described the apparatus in its preferred embodiment of interconnected associated working instrumentalities, it is apparent that changes may be made in the detailed construction of the working parts without departing from the nature and scope of the invention and I do not wish to be understood as limiting or restricting the invention to such described details of construction, but on the contrary wish to be understood as claiming broadly for the invention interconnected or associated working instrumentalities for cutting on a single reciprocating stroke a plurality of disk blanks from liner material either during a continuous or intermittent movement of the webs and this irrespective as to whether the cutting mechanism acts relative to a plurality of superposed webs of liner material or merely on a single web of liner material.

Having thus described the invention what is claimed as new and desired to be protected by Letters Patent is:

1. In an apparatus for the described purpose, the same comprising a suitable frame member, of feed means associated therewith for advancing a web of flat liner material therethrough in a substantially vertical direction, a support for a roll of liner material, a plurality of aligned reciprocating punches and a plurality of associated aligned cutting dies sustained by the frame member and between which punches and dies the web of liner material is moved, mechanism for imparting reciprocating movement to the punches for coaction with the cutting dies for the severing of a plurality of disks from the web of liner material, means for removing the punchings in a substantially horizontal direction, and means for removing the waste section of the web.

2. An apparatus for the described purpose, the same comprising means for advancing a web of liner material therethrough, cutting means comprising a plurality of aligned punch members and a plurality of associated aligned cutting die members disposed at an angle to the path of travel of the web of liner material and between which the same is advanced, said punches being arranged at an angle to the vertical and the web material where it is operated on being arranged at an angle to the horizontal, mechanism for imparting reciprocating movement to one of the series of members of the cutting means for coaction with the opposing series for the cutting from the web on a single stroke a plurality of disks, and means for leading off the punchings arranged face to face and resting on their lower edges.

3. An apparatus for the described purpose, the same comprising means for advancing a web of liner material therethrough, cutting means comprising a series of alined punch members and a plurality of associated alined cutting dies disposed obliquely to the path of travel of the web and between which the same is advanced, and mechanism for imparting reciprocating motion to one of the series of members of the cutting means for coaction with the opposing series for the cutting on a single stroke from a web advanced therebetween a plurality of disks, and means for leading off the punchings arranged face to face and resting on their lower edges.

4. An apparatus for the described purpose, the same comprising a suitable vertically disposed frame member, a backing plate carried thereby provided with a plurality of obliquely disposed openings, a cutting die secured within each of said openings, and obliquely disposed supporting member provided with a plurality of guide-ways secured to the frame member in advance of the backing plate, a series of slides mounted in said guide-ways for reciprocating movement, a punch carried by each slide for coaction with one of the cutting dies, means for reciprocating said slides in unison, and mechanism for advancing a web of liner material between said cutting dies and punches whereby there is severed therefrom on each stroke of the punches a plurality of disks.

5. An apparatus for the described purpose, the same comprising a supporting frame, mechanism for advancing a web of liner material therethrough, a series of alined punch members and a series of associated alined cutting die members between which the web is advanced, means for imparting reciprocating motion to one of said series of members for coaction with the opposing series of members for the cutting on a single stroke of a plurality of disks from a web advanced between said members, and means for receiving and supporting the disks cut from said web, said disks being arranged face to face resting on their lower edges.

6. In an apparatus for the described purpose, the combination with a supporting frame, of a plurality of alined cutting dies disposed obliquely thereof, a supporting member spaced from the cutting dies and disposed obliquely of the supporting frame, a series of punches maintained on said supporting member for reciprocating motion in alinement with the cutting dies, means for imparting reciprocating motion to said punches in unison, mechanism for advancing a plurality of superposed webs of liner material between the series of cutting dies, punches for the cutting therefrom on a

single stroke of the punches a plurality of disks, and means extending sidewise from said punches for leading off said disks arranged face to face resting on their lower edges.

7. In an apparatus for the described purpose, the combination with a frame structure, of cutting means comprising a series of cutting die members and a series of opposing punch members disposed in longitudinal alinement, mechanism for imparting reciprocating motion in unison to one series of said members of the cutting means, a holder for sustaining a plurality of rolls of liner material, and mechanism for advancing a plurality of superposed webs of said material between the dies and punches for the cutting therefrom on a single stroke of the reciprocating members a plurality of disks, means extending sidewise from said die members for leading off said disks arranged face to face and resting on their lower edges, and means controlling the discharge of the cut webs.

8. In an apparatus for the described purpose, the combination with a supporting frame, of a series of cutting dies and a series of reciprocating punches carried by said frame in longitudinal alinement, means for imparting reciprocating movement in unison to the series of punches, mechanism for advancing a plurality of superposed webs of liner material between the dies and punches for the cutting from each web on a single stroke of the punches a plurality of disks, and means extending sidewise from said dies for leading off said disks arranged face to face and resting on their lower edges.

9. In an apparatus for the described purpose, the combination with a supporting frame, a series of cutting dies carried thereby, a series of slides supported thereby and each carrying a plunger in axial alinement with the cutting die, a drive shaft for said slides, crank connections between the shaft and the punch slides for imparting reciprocating motion thereto, a holder adapted to support a plurality of rolls of liner material, feed rolls for advancing webs of said material in superposed relation between the cutting dies and punches for the cutting therefrom a plurality of disks on a single stroke of the reciprocating punches, mechanism for actuating the shaft for operating the slides of the punches and imparting movement to the feed rolls for advancing the superposed webs during the reciprocating stroke of the punches, and means extending sidewise from said dies for leading off said disks arranged face to face and resting on their lower edges.

10. In an apparatus for the described purpose, the combination with a supporting frame, of a plurality of cutting dies and a plurality of reciprocating punches carried

- by said frame in longitudinal alinement, means for imparting reciprocating movement to said punches, mechanism for continuously advancing superposed webs of flat liner material through the apparatus and during the reciprocating movement of the punches for the cutting of a plurality of disks from each of the webs on each stroke of the said punches, and sidewise extending 5 holders for leading off said disks arranged face to face and resting on their lower edges.
11. An apparatus for the described purpose, the same comprising a suitable vertically disposed frame member, a backing 15 plate carried thereby provided with a plurality of obliquely disposed openings, a cutting die secured within each of said openings, an obliquely disposed supporting member provided with a plurality of guide-ways 20 secured to the frame member in advance of the backing plate, a series of slides mounted in said guide-ways for reciprocating movement, a punch carried by each slide for co-action with one of the cutting dies, means for reciprocating said slides in unison, 25 guides for the punched disks extending sideways from said dies and leading away the punchings arranged face to face and resting on their edges, and mechanism for advancing a web of liner material between 30 said cutting dies and punches whereby there is severed therefrom on each stroke of the punches a plurality of disks.
- In testimony whereof I have signed my name to this specification in the presence of 35 two subscribing witnesses.
